UNITED STATES PATENT OFFICE.

WILLIAM E. CHIPMAN, OF EASTON, PENNSYLVANIA.

AUXILIARY GUIDING DEVICE FOR SEWING-MACHINES.

1,358,705.

Specification of Letters Patent. Patented Nov. 16, 1920.

Application filed March 27, 1919. Serial No. 285,510.

To all whom it may concern:

Be it known that I, WILLIAM E. CHIPMAN, a citizen of the United States, and a resident of Easton, in the county of Northampton and State of Pennsylvania, have invented certain new and useful Improvements in Auxiliary Guiding Devices for Sewing-Machines, whereof the following is a specification, reference being had to the accompanying drawings.

The invention relates to auxiliary guiding devices useful in connection with sewing machines or the like, and is more particularly directed to adjunctive devices of the character specified by which hosiery or other tubular fabric may be accurately guided to the sewing elements of the machine.

The invention may be advantageously employed, for example, in the manufacture of imitations of full fashioned hosiery by the formation of a false suture at the back of a seamless stocking having the appearance of the suture characteristic of the preferred species. In the manufacture of such imitations heretofore, considerable difficulty has been experienced in producing a false seam along a straight line, or rather in parallelism with the longitudinal lines of the knitting wales in the stocking leg. Such deviation from a straight course resulted in unsightliness and the product was accordingly unsatisfactory.

In order to overcome these difficulties, I have devised an apparatus which is not only functional as an auxiliary guide, but which also serves through the aid of certain supplemental features, as a means whereby the stocking may be first of all accurately centered before being advanced to the sewing machine.

The organization whereby I accomplish the results above pointed out will be best understood from the detailed description which follows.

In the drawings, Figure I, is a plan view of my improved auxiliary guiding means in operative association with a suitable sewing machine.

Fig. II, is a side elevation of the organization illustrated in Fig. I.

Fig. III, is an end elevation of the mounting board and its supporting pedestal as viewed from the left of Fig. II.

Fig. IV, is a detail view of the inner or attachment end of the board.

Fig. V, is a fragmentary detail view on an enlarged scale, of a portion of the mounting board and a stocking in position thereon, illustrating the gaging aperture by the aid of which the stocking is properly centered preparatory to being advanced to the sewing machine.

Fig. VI, is a view of the mounting board in association with the feeding devices of the sewing machine, also showing a stocking advanced into engagement with the latter, and

Fig. VII, illustrates diagrammatically, a stocking as it appears after the sewing operation.

Referring first to Figs. I to IV, inclusive, the organization constituting my invention consists of a guiding device comprehensively indicated at 1, arranged in proper alinement with a sewing machine 15, supported upon a suitable work table 20.

The guiding apparatus 1, consists of a thin flexible tongue or board 2, preferably wood, supported after the manner of a cantaliver. This board is preferably disposed at an inclination for the convenience of the operative and projects from an anchorage in the form of a pedestal comprising a pair of uprights 3—3, bolted at their bases to the floor and supporting between the upper ends a clamp member 4, having an inclined extension 5. This extension is centrally pierced by a threaded aperture 6, for the reception of a screw bolt 7, which, in co-operation with a plate 8, serves to clamp the inner end of the mounting board 2, to the pedestal. In order to permit its adjustability, with respect to the sewing machine, board 2, is slotted as shown at 9, in Fig. IV. The outer or free end of the board, normally registers, with the supporting plate 16, of the sewing machine, but by virtue of its flexibility may be readily deflected to facilitate the mounting of the stocking. At a point corresponding to the location of the heel of the stocking, the outer end of the mounting board is provided with a gaging aperture 10, having preferably a substantially circular outline. Directly beneath the board, and in line with the aperture 10, is located a lamp 11, preferably an electric light, attached to a block 12, projecting laterally from the edge of the work table. Through the co-operative assistance of these elements,

105 and in consideration of the translucency of the knitted fabric, I am enabled to properly 110

center the stocking upon the board preparatory to advancing the same to the sewing machine, in a manner which will be subsequently explained.

5 The sewing machine 15, more or less diagrammatically shown herein, is of well known construction and in itself forms no part of the present invention. In Fig. VI, I have however shown a few of its parts in 10 detail so as to more clearly show the exact relation of the end of the mounting board to the feed elements of the machine. In said figure, the work supporting plate already referred to is indicated at 16, the presser foot at 17, a coöperative guide finger at 18, and the sewing needle at 19.

15 The operation of my invention is as follows:

20 The stocking S, turned inside out, is slipped over the mounting board 2, and adjusted so that the heel is brought into coincidence with the end of the board which is rounded, as shown in Fig. V, in proper conformity therewith. The proportions of the 25 board are such that the fabric is slightly stretched in order to lie perfectly flat. The gaging aperture 10, is so located, as previously described that the longitudinal lines of demarcation at each side of the stocking 30 resulting from the heel reinforcement, are plainly visible by reason of the translucency of the knitted fabric through the aperture 10, under the aid of the luminosity afforded from beneath by the lamp 11. After these 35 lines of demarcation are brought into accurate coincidence, the intermediate portions of the stocking become properly centered on the board and the operative is further guided by coöordinating the longitudinal 40 lines of the knitting wales in the leg portion, with the straight edge of the board in properly determining the position of the remainder of the stocking. After the stocking is thus arranged upon the board, the operative grasps the foot end and advances the 45 same beneath the presser foot 17, of the sewing machine 15, under the assistance afforded by the guide finger 18, as shown in Fig. VI. The machine is then set in motion and the stocking run through under the 50 guidance of the mounting board 2, the operative, in the meanwhile, maintaining by hand a sufficient tension to prevent gathering and also preserving the coöordination 55 above referred to.

It is to be remembered that this operation is performed upon seamless hosiery, the leg portions of which are plain cylindrical tubes with little or no fashioning, so that the 60 stitching is effected along a straight line in contradistinction to the uniting of the curvilinear edges, of flat knitted or full fashioned hosiery. The operation therefore results in producing a longitudinal line along 65 the back of the stocking as represented at

21, in Fig. VII, which after the stocking is turned right side out, has the appearance of the seam characteristic of full fashioned hosiery. The fashioned contour represented in Fig. VII, is obtained through a pressing 70 operation such as is ordinarily practised in finishing seamless hosiery.

Having thus described my invention, I claim:

1. In a device of the character described, 75 the combination with a sewing machine, of an auxiliary means for guiding a folded stocking to the feeding devices of said machine; and means for initially centering the usual front and rear fold of the stocking 80 accurately upon the auxiliary guiding means.

2. In a device of the character described, 85 the combination with a sewing machine, of an auxiliary means adapted to be inserted within the leg of a stocking for guiding the same to the feeding devices of said machine, and means for initially centering the stocking upon said auxiliary guiding means by superposition of corresponding side portions 90 at the heel.

3. In a device of the character described, 95 the combination of an auxiliary guiding means including a mounting board over which a stocking is stretched, said board having a gaging aperture at the region occupied by the stocking heel, whereby, through the translucency of the knitted fabric, the longitudinal limiting edges of the heel reinforcement at the sides of the stocking may be brought into registry and the stocking thereby accurately centered upon the board; and a sewing machine alined with the mounting board and adapted to receive the stocking under the guidance of said 100 board.

4. In a device of the character described, 105 the combination of an auxiliary guiding means including a mounting board over which a stocking is stretched, said board having a gaging aperture at the region occupied by the stocking heel; means for illuminating said aperture, whereby, through the translucency of the knitted fabric, the longitudinal limiting edges of the heel reinforcement at the sides of the stocking may be brought into registry and the stocking thereby accurately centered on the board; and a sewing machine alined with said board adapted to receive the stocking under 110 the guidance of said board.

5. In a device of the character described, 115 the combination of an auxiliary guiding means including a mounting board over which a stocking is stretched, said board having a gaging aperture at the region occupied by the stocking heel; lighting means located below, and in line with said aperture, whereby, through the translucency of the knitted fabric, the longitudinal limiting 120

edges of the heel reinforcement at the sides of the stocking may be brought into registry and the stocking thereby accurately centered on the board; and a sewing machine 5 alined with said board adapted to receive the stocking under the guidance of said board.

6. In a device of the character described, the combination with a sewing machine, of 10 an auxiliary guiding means including a flexible mounting board for a stocking, said board having the form of a cantaliver with its free end normally in accurate guiding relation with the feeding devices of the 15 sewing machine and its longitudinal edge parallel with the vertical plane of feed, but capable of being deflected to facilitate the mounting of the work thereon.

7. In a device of the character described, 20 the combination with a sewing machine, of a guiding means including a flexible mounting board for a stocking, said board having the form of a cantaliver with its free end normally in accurate guiding relation with

the feeding devices of the sewing machine 25 and its length extending in the direction of feed thereof; and an anchorage for the said board consisting of a floor pedestal formed with a clamp within which the opposite end of the board is firmly but adjustably se- 30 cured.

8. In a device of the character described, the combination of a sewing machine supported at a level convenient to the operative; a guiding means, including a mount- 35 ing board for a stocking in the form of a cantaliver inclined upwardly toward the machine, and having its free end in guiding registry with the feeding devices of the ma- 40 chine and its longitudinal edge parallel with the vertical plane of feed.

In testimony whereof, I have hereunto signed my name at Easton, Pa., this 22nd day of March, 1919.

WILLIAM E. CHIPMAN.
